[57] **CLAIM**

The ornamental design for a flotation device, as shown and described.

DESCRIPTION

FIG. 1 is a front perspective view of a flotation device showing my new design;

FIG. 2 is a left side elevational view thereof;

FIG. 3 is a right side elevational view thereof;

FIG. 4 is a top plan view thereof;

FIG. 5 is a front elevational view thereof;

FIG. 6 is a rear elevational view thereof;

FIG. 7 is a bottom plan view thereof;

FIG. 8 is a rear elevational view of a second embodiment of the flotation device; and,

FIG. 9 is a rear elevational view of a third embodiment of the flotation device.

The sole difference among the first, second and third embodiments being in the configuration of the back panel of the flotation device.
